[57] **CLAIM**

The ornamental design for a base bracket for supporting
a brick veneer wall from a house foundation wall, sub-
stantially as shown.

DESCRIPTION

FIG. 1 is a front perspective view of a base bracket for
supporting a brick veneer wall from a house foundation
wall showing my new design;
FIG. 2 is a top plan view;
FIG. 3 is a front elevational view;
FIG. 4 is a side elevational view;
FIG. 5 is a rear elevational view,
FIG. 6 is a bottom plan view.
